UNITED STATES PATENT OFFICE.

HIRAM H. HIRSCH, OF PHILADELPHIA, PENNSYLVANIA.

PORTABLE ELECTRIC-LIGHTING APPARATUS.

1,097,022.

Specification of Letters Patent. Patented May 19, 1914.

Application filed May 29, 1913. Serial No. 770,752.

To all whom it may concern:

Be it known that I, HIRAM H. HIRSCH, a citizen of the United States, residing at Philadelphia, in the State of Pennsylvania, have invented a certain new and useful Improvement in Portable Electric-Lighting Apparatus, whereof the following is a specification, reference being had to the accompanying drawing.

10 My invention relates to apparatus including an incandescent lamp in co-operative relation with a storage battery provided with means to attach it to the person of a miner or other operator, and provides a safety casing for the lamp designed to extinguish the light to prevent ignition of fire-damp or other explosive gases when said casing is subjected to stresses tending to break the lamp.

15 As hereinafter described my invention includes a lamp casing and removable cover provided with a transparent lens or panel, normally assembled in substantially hermetical relation; said casing having distinct oppositely polarized elements included in the lamp circuit, so constructed and arranged that they are shifted to modify the lamp circuit and instantaneously extinguish the lamp, whenever said casing is crushed or punctured. Said casing is detachably connected with a socket having an angle plate for engagement with a miner's cap, and a flexible connector extending from said socket comprising an outer flexible metallic tube constituting one conductor and inclosing a flexible wire constituting the other conductor; the opposite end of said connector being shaped for detachable connection with a battery socket with which said lamp casing may be directly connected without the intervention of said flexible connector.

My invention includes the various novel features of construction and arrangement hereinafter more definitely specified; the flexible connector and appurtenances thereof being claimed in my copending application Serial #770,753 for Letters Patent of the United States.

In the drawings: Figure I is an enlarged longitudinal sectional view of a lamp casing and flexible connector embodying my improvement. Fig. II is a fragmentary front elevation of said casing with the cover removed. Fig. III is a front elevation of the insulating ring shown in Fig. I; but of the actual size.

In said figures; the lamp casing includes the outer metallic cup-shaped shell 1 having the annular ring seat 2 within the screw threaded flange 3 at its larger end, and having the cylindrical tubular shank 5 at its opposite end. The split ring 6 of insulating material, conveniently hard rubber or a rubber composition, is seated in said screw flange 3 and has the two annular grooves 8 and 9 interrupted by the abutment 10 formed by an ungrooved portion of said ring 6. Said ring 6 has diametrically opposite panel recesses 12 and 13 to receive the respectively opposite end corners of the rectangular plane transparent panel 15, conveniently formed of glass, extending transversely with respect to the axis of said casing. Said casing is provided with the removable cover including the annular metallic frame 17 having the screw thread 18 fitted to the screw thread 3 on said shell 1 and having the flange 19 overlapping the edge of the circular concavo-convex transparent panel 21, which is conveniently formed of molded glass, and may be a lens. The resilient gasket 22, conveniently formed of soft rubber, is fitted in said cover band 17 and adapted to bear upon the edge of said panel 21 and upon said insulating ring 6 in said shell 1 so as to hermetically seal the joint between them.

The plug of insulating material 24 is fitted in said outer shell shank 5 and prevented from rotating by the key 25 which extends in the keyway 26 in said plug 24 and has its inner end projecting through the opening 28 in said outer shell shank. The intermediate cup-shaped shell 29 has the flange 30 at its outer end fitted in the groove 8 of said ring 6, and has the notch 32 coincident with said abutment 10 in said ring which prevents said shell from rotating therein. Said intermediate shell 29 has the cylindrical shank 34 which is rigidly connected with said plug 24 by the axial bolt 35, which extends through said plug, having the head 36 within said intermediate shell 29 and the nut 37 exterior to said plug 24 serving as the negative electrical terminal of said lamp casing, the positive terminal being said outer shell shank 5.

The inner parabolic reflector shell 40 has the flange 41 fitted to the groove 9 in said ring 6 and has the notch 42 coincident with the abutment 10 in said ring so that relative rotation of said shell is prevented. Said in-

2
ner shell 40 has the cylindrical shank 43 carrying the spring contact 45 having its inner end extending parallel with the axis of the lamp casing in electrical contact with the outer surface of said shank of the shell 40, the opposite end of said spring 45 being normally upheld by said panel 15 so as to press the bight 46 of said spring into electrical contact with the outer shell 1 as shown in Fig. I. Said spring 45 is rigidly connected with said inner reflector shell 40 by the metallic collar 48 encircling said shank 43 and the end of said spring as shown in Fig. I; said collar 48, spring 45 and shank 43 being electrically connected with the screw threaded bushing 50 in the latter by solder. Said bushing 50 fits the metallic screw threaded sleeve terminal 52 of the incandescent electric lamp 53 which has the axial metallic terminal 54 in contact with the head 36 of said bolt 35; said inner shell 40 being held in concentric relation with said intermediate shell 29 by the band 56 of insulating material encircling said shank 43 on said inner shell 40 and extending into the shank 34 of the intermediate shell 29.

The tubular head socket 58 is fitted to extend over the plug 24 and shank 25 on said outer shell 1 of the lamp casing and has the bayonet slot 59 arranged to engage the projecting end of said key 25; the slotted end of said socket being reinforced by the band 60 rigidly connected therewith, by solder. Said socket 58 has the outer shoulder 61 against which fits the flange 63 of the angle plate 64 which is fitted for detachable engagement with the bracket 65 in the miner's head cap 66. The inner shoulder 68 in said shell 58 determines the position of the insulating diaphragm 69 which supports the metallic thimble 70 in which is seated the contact spring 71 arranged to make detachable electrical connection with said nut 37 on the lamp casing. The flexible metal tube 73, conveniently formed of a spirally wrapped strip having interlocking edges, is rigidly connected with said socket 58 at one end and with the hollow terminal elbow 74 at the opposite end; the junction of said tube 73 with said elbow being reinforced by the spiral spring cover 75 which is rigidly connected with said elbow at one end as shown in Fig. I. The end of said elbow opposite from said spring is cylindrical, of the same diameter as the lamp casing shank 5, and has a locking projection 76 like the projecting end of said key 25 so that said casing and elbow may be interchangeably fitted in the battery casing socket 78 in electrical connection with the battery 80; said flexible tube 73 serving as one conductor, the other conductor being the flexible wire 82 extending through said flexible tube 73 from which it is insulated by its covering 83. Said wire is electrically connected with

said contact spring 71 in said head socket 58, and with the terminal eyelet 85 which is mounted in the insulating bushing 86 in the metallic cap 87 in said elbow 74. As indicated in Fig. I said battery 80 is connected upon one side with said socket 78 and upon the opposite side with the terminal 89 which is in electrical contact with said eyelet 85. As indicated, said outer shell 1 and inner shell 40 are positively polarized by suitable connection with said battery 80, and said intermediate shell 29 is negatively polarized; so that if said outer shell 1 be crushed into contact with the intermediate shell 29 said lamp 53 is short circuited and extinguished. Moreover, if said glass panel 15 be broken or otherwise displaced said spring 45 snaps away from said outer shell 1 so as to break the circuit and extinguish said lamp. Furthermore, said spring 45 which normally electrically connects said inner and outer shells as shown in Fig. I, through the notch 32 in the intermediate shell 29 which is normally held out of electrical contact with said spring by the insulating abutment 10 in the ring 6, extends so close to the intermediate shell 29 that very slight distortion of the lamp casing causes said spring to contact with said intermediate shell and thus short circuit and extinguish the lamp. In other words, it is to be understood that both the metallic and transparent elements of said lamp casing are crushable so that when either is crushed or displaced from its normal position the electric circuit is modified to extinguish the lamp before it is possible for any incandescent portion thereof to ignite fire-damp or other inflammable gases from the atmosphere surrounding said casing.

I do not desire to limit myself to the precise details of construction and arrangement herein set forth, as it is obvious that various modifications may be made therein without departing from the essential features of my invention as defined in the appended claims.

I claim:—

1. In a portable electric lighting apparatus, a lamp casing including an outer metallic cup shaped shell having an annular ring seat and a screw threaded flange at its larger end and a cylindrical tubular shank at its opposite end; a split ring of insulating material in said seat, having two annular grooves interrupted by an abutment formed by an ungrooved portion of said ring, and having diametrically opposite panel recesses; a rectangular plane transparent frangible panel, extending transversely with respect to the axis of said casing and having its diametrically opposite ends fitted in said recesses in said ring; a removable cover for said shell including an annular metallic screw threaded frame fitted

to the screw thread on said shell, and a circular concavo-convex transparent frangible panel fitted in said frame; a resilient gasket fitted in said frame, arranged to bear upon the edge of said circular panel and upon said insulating ring in said shell and hermetically seal the joint between them; a plug of insulating material in said outer shell shank; a keyway in said plug within said shank; a key extending in said keyway and having one end extending through an opening in said outer shell, forming a locking projection; an intermediate cup shaped shell having a flange at its outer end fitted in one of the grooves of said insulating ring, having a notch coincident with said abutment in said ring, and a cylindrical shank; a bolt extending axially through said plug, having a head within said intermediate shell and a nut exterior to said plug holding said intermediate shell in rigid relation with said plug and serving as an electrical terminal; an inner parabolic reflector shell having a flange fitted to the other groove in said ring, having a notch coincident with the abutment in said ring, and a cylindrical shank; a spring contact having one end extending parallel with the axis of the lamp casing in contact with the outer surface of the cylindrical shank of said reflector shell and having its opposite end extending in the notches in said intermediate and inner shells and normally resting upon the adjacent end of said rectangular panel; said rectangular panel normally holding said spring in electrical contact with said outer shell; a metallic collar encircling the cylindrical shank on said inner shell, holding said spring thereon; a screw threaded lamp socket bushing in said inner shell shank electrically connected with said shell and spring; and, a band of insulating material encircling the shank on said inner shell and extending into the shank on said intermediate shell; whereby said casing is adapted to hold an incandescent electric lamp bulb having a metallic sleeve fitted to the bushing in said inner shell, and an axial terminal fitted to contact with the head of said bolt.

2. In a portable electric lighting apparatus, a lamp casing including an outer metallic shell having a screw threaded flange at its larger end and a cylindrical tubular shank at its opposite end; an insulating ring in said flange, having two annular grooves and diametrically opposite panel recesses; a rectangular plane transparent frangible panel, extending transversely with respect to the axis of said casing and having its diametrically opposite ends fitted in said recesses in said ring; a removable cover for said shell including an annular metallic screw threaded frame fitted to the screw thread on said shell, and a circular trans-

parent frangible panel fitted in said frame; a resilient gasket fitted in said frame, arranged to bear upon the edge of said circular panel and upon said insulating ring in said shell and hermetically seal the joint between them; a plug of insulating material in said outer shell shank; a keyway in said plug within said shank; a key extending in said keyway and having one end extending through an opening in said outer shell, forming a locking projection; an intermediate shell having a flange at its outer end fitted in one of the grooves of said insulating ring, and a cylindrical shank; a bolt extending axially through said plug, holding said intermediate shell in rigid relation with said plug and serving as an electrical terminal; an inner reflector shell having a flange fitted in the other groove in said ring, and a cylindrical shank; a spring contact having one end connected with said reflector shell and having its opposite end extending in the notches in said intermediate and inner shells and normally resting upon the adjacent end of said rectangular panel; said rectangular panel normally holding said spring in electrical contact with said outer shell; a lamp socket bushing in said inner shell shank electrically connected with said shell and spring; and, a band of insulating material encircling the shank on said inner shell and extending into the shank on said intermediate shell; whereby said casing is adapted to hold an incandescent electric lamp bulb having a metallic sleeve fitted to the bushing in said inner shell, and an axial terminal fitted to contact with said bolt.

3. In a portable electric lighting apparatus, a lamp casing including an outer shell having a connecting flange at its larger end and a tubular shank at its opposite end; an insulating ring in said flange, having two annular grooves and panel recesses; a transparent frangible panel, extending transversely with respect to the axis of said casing and fitted in said recesses in said ring; a removable cover for said shell including an annular frame fitted to said connecting flange on said shell, and a circular transparent frangible panel fitted in said frame; a resilient gasket fitted in said frame, arranged to bear upon the edge of said circular panel and upon said insulating ring in said shell and seal the joint between them; a plug of insulating material in said outer shell shank; an intermediate shell having a flange at its outer end fitted in one of the grooves of said insulating ring, and a shank; a bolt extending through said plug, holding said intermediate shell in rigid relation with said plug and serving as an electrical terminal; an inner shell having a flange fitted in the other groove in said ring, and a shank; a spring contact having one end connected with said inner shell and having its opposite

- end extending in notches in said intermediate and inner shells and normally resting upon the adjacent end of said first panel; said first panel normally holding said spring in electrical contact with said outer shell; and a lamp socket bushing in said inner shell shank electrically connected with said shell and spring; whereby said casing is adapted to hold an incandescent electric lamp bulb having a metallic sleeve fitted to the bushing in said inner shell, and an axial terminal fitted to contact with said bolt.
4. In a portable electric lighting apparatus, a lamp casing including an outer shell having a connecting flange at its larger end and a shank at its opposite end; an insulating ring in said flange, having two annular grooves and panel recesses; a transparent frangible panel, fitted in said recesses 15 in said ring; a removable cover for said shell including an annular frame fitted to said connecting flange on said shell, and a second transparent frangible panel fitted in said frame; a resilient gasket fitted in said frame, 20 arranged to bear upon the edge of said second panel and upon said insulating ring in said shell and seal the joint between them; an intermediate shell having a flange at its outer end fitted in one of the grooves of 25 said insulating ring, and a shank; an inner shell having a flange fitted in the other groove in said ring, and a shank; a spring contact having one end connected with said inner shell and having its opposite end normally resting upon the adjacent end of said 30 first panel; said first panel normally holding said spring in electrical contact with said outer shell; and a lamp socket bushing in said inner shell shank electrically connected with said shell and spring.
5. In a portable electric lighting apparatus, a lamp casing including an outer metallic shell having a screw threaded flange at its larger end and a cylindrical 35 tubular shank at its opposite end; an insulating ring in said seat, having two annular grooves and diametrically opposite panel recesses; a rectangular plane transparent frangible panel, extending transversely with respect to the axis of said casing and having its diametrically opposite ends fitted in said recesses in said ring; a removable cover for said shell including an annular metallic screw threaded frame fitted 40 in the screw thread on said shell, and a circular transparent frangible panel fitted in said frame; a resilient gasket fitted in said frame, arranged to bear upon the edge of said circular panel and upon said insulating ring in said shell and hermetically seal the joint between them; an intermediate shell having a flange at its outer end fitted in one of the grooves of said insulating ring, and a cylindrical shank; a spring contact having one end connected with said reflector shell and having its opposite end extending in the notches in said intermediate and inner shells and normally resting upon the adjacent end of said rectangular panel; said rectangular panel normally holding said spring in electrical contact with said outer shell; and a lamp socket bushing in said inner shell shank electrically connected with said shell and spring.
6. In a portable electric lighting apparatus, a lamp casing including an outer shell having a screw threaded flange at its larger end and a cylindrical tubular shank at its opposite end; an insulating ring in said seat, having two annular grooves and panel recesses; a transparent frangible panel, extending transversely with respect to the axis of said casing and fitted in said recesses in said ring; a removable cover for said shell

including an annular screw threaded frame fitted to the screw thread on said shell, and a circular transparent frangible panel fitted in said frame; a resilient gasket fitted in said frame, arranged to bear upon the edge of said circular panel and upon said insulating ring in said shell and seal the joint between them; an intermediate shell having a flange at its outer end fitted in one of the grooves of said insulating ring, and a cylindrical shank; an inner reflector shell having a flange fitted in the other groove in said ring, and a cylindrical shank; a spring contact having one end connected with said reflector shell and having its opposite end extending in the notches in said intermediate and inner shells and normally resting upon the adjacent end of said rectangular panel; said rectangular panel normally holding said spring in electrical contact with said outer shell; a lamp socket bushing in said inner shell shank electrically connected with said shell and spring; and, a band of insulating material encircling the shank on said inner shell and extending into the shank on said intermediate shell.

8. In a portable electric lighting apparatus, a lamp casing including an outer metallic shell having a screw threaded flange at its larger end and a cylindrical tubular shank at its opposite end; an insulating ring in said flange, having two annular grooves; an intermediate shell having a flange at its outer end fitted in one of the grooves of said insulating ring; an inner reflector shell having a flange fitted in the other groove in said ring; a contact spring permanently connected with said reflector shell and normally in contact with said outer shell; and a lamp socket bushing in said inner shell electrically connected therewith; whereby said contact spring coacts with the other elements of the apparatus to break the lamp circuit when the lamp becomes exposed to the atmosphere.

9. In a portable electric lighting apparatus, a lamp casing including an outer metallic shell having a connecting flange at its larger end and a tubular shank at its opposite end; an insulating ring in said flange, having two annular grooves; an intermediate shell having a flange at its outer end fitted in one of the grooves of said insulating ring; an inner reflector shell having a flange fitted in the other groove in said ring; a contact spring permanently connected with said reflector shell and normally in contact with said outer shell; and a lamp socket bushing in said inner shell electrically connected therewith; whereby said contact spring coacts with the other elements of the apparatus to break the lamp circuit when the lamp becomes exposed to the atmosphere.

10. In a portable electric lighting apparatus, a lamp casing including an outer

metallic shell; an insulating ring in said flange, having two annular grooves; an intermediate shell having a flange at its outer end fitted in one of the grooves of said insulating ring; an inner reflector shell having a flange fitted in the other groove in said ring; and a lamp socket bushing in said inner shell electrically connected therewith.

11. In a portable electric lighting apparatus, a lamp casing including an outer metallic shell having an annular ring seat and a screw threaded flange at its larger end and a cylindrical tubular shank at its opposite end; a split ring of insulating material in said seat, having two annular grooves interrupted by an abutment formed by an un-grooved portion of said ring, and having panel recesses; a frangible panel fitted in said recesses in said ring; a removable cover for said shell; an intermediate shell having a flange at its outer end fitted in one of the grooves of said insulating ring, having a notch coincident with said abutment in said ring; an inner parabolic reflector shell having a flange fitted to the other groove in said ring, having a notch coincident with the abutment in said ring, and a shank; a spring contact having one end connected with said reflector shell and having its opposite end extending in the notches in said intermediate and inner shells and normally resting upon said panel; said panel normally holding said spring in electrical contact with said outer shell; a lamp socket bushing in said inner shell electrically connected with said shell and spring; and, a band of insulating material encircling the shank on said inner shell and extending into the shank on said intermediate shell.

12. In a portable electric lighting apparatus, a lamp casing including an outer metallic shell having an annular ring seat and a connecting flange at its larger end and a shank at its opposite end; a split ring of insulating material in said seat, having two annular grooves interrupted by an abutment, and having panel recesses; a frangible panel fitted in said recesses in said ring; a removable cover for said shell; an intermediate shell having a flange at its outer end fitted in one of the grooves of said insulating ring, having a notch engaging said abutment in said ring; an inner reflector shell having a flange fitted to the other groove in said ring, having a notch engaging the abutment in said ring, and a shank; a spring contact having one end connected with said reflector shell and having its opposite end extending in the notches in said intermediate and inner shells and normally resting upon said panel; said panel normally holding said spring in electrical contact with said outer shell; a lamp socket bushing in said inner shell electrically connected with said shell and spring; and, a band of insulating material encircling the

shank on said inner shell and extending into the shank on said intermediate shell.

13. In a portable electric lighting apparatus, a lamp casing including an outer metallic shell having a connecting flange at its larger end and a shank at its opposite end; a split ring of insulating material in said seat, having two annular grooves, and having panel recesses; a frangible panel fitted in said recesses in said ring; a removable cover for said shell; an intermediate shell having a flange at its outer end fitted in one of the grooves of said insulating ring; an inner reflector shell having a flange fitted to the other groove in said ring,

end a shank; and a spring contact having one end connected with said reflector shell and having its opposite end normally resting upon said panel; said panel normally holding said spring in electrical contact with said outer shell; a lamp socket bushing in said inner shell electrically connected with said shell and spring.

In testimony whereof, I have hereunto signed my name at Philadelphia, Pennsylvania, this 24th day of May, 1913.
